SEMAUTOMATIC WATER SOFTENER

Filed June 9, 1928

UNITED STATES PATENT OFFICE

OSCAR W. JOHNSON, OF ROCKFORD, ILLINOIS, ASSIGNOR, BY MESNE ASSIGNMENTS, TO THE PERMUTIT COMPANY, OF WILMINGTON, DELAWARE, A CORPORATION OF DELAWARE

SEMI-AUTOMATIC WATER SOFTENER

Application filed June 9, 1928. Serial No. 284,248.

This invention relates to base-exchange water softeners generally, but is more particularly concerned with a semi-automatic softener, that is to say, a softener wherein the commencement of the regeneration is under manual control and the regeneration itself is arranged to be automatically controlled.

The principal object of the present invention is to provide a valve operating mechanism for a semi-automatic softener arranged to be manually operated at the time when regeneration is required so as to bring the valve to the first position of regeneration, for the salt wash, this operation of the mechanism serving to store energy by the raising of a weight, winding of a spring, or the like, sufficient to insure the subsequent automatic operation of the valve operating mechanism to shift the valve from the salt wash to the rinse position and, again, from the rinse position back to the softening position.

Still another important feature of my invention consists in providing a valve operating mechanism including means for releasably holding the valve in the salt wash and rinse positions, the said means being arranged to be operated by a trip bucket into which a certain definite portion of the waste water during the salt wash and during the rinse is arranged to be diverted, the trip bucket when partly loaded in this manner serving to release the valve for movement from salt wash position to rinse position and when loaded a still further predetermined amount serving to release the valve a second time for movement from rinse position to softening position. With this arrangement I am enabled to vary the duration of the salt wash and rinse operations by varying the portion of the waste water directed into the trip bucket or by varying the tension in a spring against which the trip bucket is arranged to operate.

The invention is illustrated in the accompanying drawing wherein—

Figure 1 is a view of a water softening apparatus equipped with my improved mechanism for the semi-automatic control of the operation thereof; and

Fig. 2 is a front elevation of the mechanism itself on a larger scale.

The water softening apparatus in connection with which I have illustrated my invention comprises a softener tank 5 and a brine tank 6, the latter being preferably of the type wherein a charge of brine is produced between regenerations, this type being shown in the Sweeney Patent 1,693,829 issued December 4, 1928. The invention, however, is not limited to use with a softener having this or any other type of brine tank, but may, for example, be applied to a softener designed for direct internal dry salting like many domestic hand-operated softeners. Also, while I have, for the sake of simplicity, shown a single multiple port valve 7 preferably of a plate type it should be understood that the invention is not limited to use either of a single valve, inasmuch as two or more interconnected valves might be employed, or a valve or valves of the particular type referred to, inasmuch as plunger or plug-type valves are available suitable for the present purpose. Reference may be had, for example, to Harwood et al., Patent 1,593,800, issued July 20, 1926, showing a multiple port valve adapted to control the operation of a softener as herein contemplated. In view of this reference it will not be necessary to go into a discussion of the construction of the valve proper. It will suffice for the present purposes merely to indicate the various pipe connections leading to and from the valve.

The hard water is supplied through pipe 8 and during normal softening operation is conducted through the valve to pipe 9 leading to the bottom of the softener. The softened water leaving the top of the tank 5 is conducted through pipe 10 and through the valve 7 to the service pipe 11. At the time of regeneration, when the valve is shifted to what I prefer to call the salt wash position, the hard water supplied through the pipe 8, after passage through the valve 7, is conducted through pipe 12 to the brine tank 6 and displaces the brine therefrom, as described in the Sweeney patent above referred to. The brine is conducted through pipe 13 and, after passage through the valve 7, passes upwardly through pipe 10, downwardly through softener tank 5, and out of the bottom of the

tank through pipe 9. The latter conducts this waste water, namely, spent brine containing lime and magnesium, to the waste pipe 14, the valve 7 in the salt wash position serving 5 to establish communication between the pipes 9 and 14. Following the salt wash, when the valve is shifted to the rinse position, the hard water supplied through the pipe 8, after passage through the valve 7, is conducted 10 through pipe 9 to the bottom of the softener tank 5 for passage upwardly therethrough to rinse the mineral bed and also displace any hard water from the head space in the tank injected during the salt wash. Incidentally, 15 as described in my Patent 1,628,541, issued May 10, 1927, this upflow serves to pick up brine from a residual pool in the bottom of the tank and carry the same up through the bed to regenerate the upper strata of the mineral bed which, toward the end of the down-flow during the salt wash, was rendered more or less exhausted by contact with the hard water. The waste water leaving the top of the tank is conducted through pipe 10 and, 20 after passage through the valve 7, is conducted through waste pipe 14 to the sewer or other waste receptacle. Following the rinse, when the valve 7 is shifted back to the softening position the normal direction of flow for softening, as first above described, is resumed.

According to the present invention the valve 7, as best appears in Fig. 2, is mounted on a bracket 15 or other suitable support fastened, as indicated at 16 (Fig. 1), to the side 25 of the tank and has a pulley or drum 17 fastened to the stem or drive shaft 18 thereof. The pulley or other equivalent element may be provided with any suitable means tending normally to turn the same in one direction and while I have shown a cable 19 wound about the periphery of the pulley and having weights 20 suspended thereon, it will be evident that a spring or other equivalent means might be employed. The valve, as 30 appears from the description above, is arranged to occupy any one of three positions, namely, softening, salt wash, and rinse. Arms A and B, fastened to the pulley 17 preferably as indicated at 21 to turn with it 35 and the stem 18, are arranged to determine the three operative positions of the valve. The arm A, it should now be noted, is slightly longer than the arm B. This difference in length plays a part in the shifting of the 40 valve from the salt wash position to the rinse position, when the arm B, because of its smaller length, is free to pass the stop C, whereas the arm A, because of its greater length, is arranged to come into engagement 45 with the stop. The stop C is provided on a tiltable beam 22 pivoted as at 23, to a lateral extension 24 of the bracket 15. The beam 22 normally occupies a substantially vertical position, being held in contact with 50 a set screw 25 by means of a coiled tension

spring 26, one end of which is fastened to the upper end of the beam 22 and the other end of which is fastened to an adjustable screw 27. The latter passes freely through an opening in a lug 28 provided on the bracket 15 and has an adjusting nut 29 threaded on the projecting end thereof. When the beam is in its normal vertical position the stop C is projected to the left sufficiently to lie in the path of the end of the arm B and to hold the valve against turning under the action of the weight 20. The beam 22 is, however, arranged to be tilted when a trip bucket 30 is loaded to a certain extent in a novel manner presently to be described. The bucket 30 is suspended from an arm 31 extending laterally from the beam 22 on the opposite side from the spring 26 so that the load of the bucket tends to counteract the pull of the spring. The beam is arranged 55 to be tilted from its normal position when the bucket 30 has been partially filled, this movement being sufficient to afford clearance for the arm B to swing past the stop C, and the beam is arranged to be further tilted when the bucket has been loaded a still further amount or nearly filled, in which position of the beam the stop C is retracted far enough to allow the longer arm A to pass the same. The loading of the bucket is accomplished 60 by diverting a certain definite portion of the waste water during the salt wash and during the rinse. It is during the salt wash that the bucket is loaded sufficiently with the spent brine to tilt the beam to allow the arm B to pass the stop C and it is during the rinse that the bucket is loaded a still further amount with waste water to tilt the beam to allow arm A to pass the stop C. In this way, it will be evident that the duration of the salt wash can be determined accurately and likewise the duration of the 65 rinse. The duration of the one is not dependent on the duration of the other; the arms A and B can be made as long or as short 70 as need be so that the salt wash and rinse steps can be prolonged or shortened as conditions seem to warrant. While the arms A and B may be provided of a certain fixed length suitable for average requirements it 75 will be evident that some variations one way or another might be desired in installations using different minerals and for that reason the arms are shown as adjustably secured to the pulley at 21 to permit the same to be extended or retracted as desired. For the purpose of diverting a portion of the waste water from the pipe 14, I have provided a fitting 32 having a restricted outlet opening 33 therein and on the upstream side of this opening having tapped in a by-pass tube 34 leading to the trip bucket 30. The size of the tube 34 may be so proportioned with respect to the size of the opening 33 that a definite portion of the waste water will be by- 80 85 90 95 100 105 110 115 120 125 130

passed to the bucket 30, but I prefer to provide in addition a regulating valve 35 to permit variation in the restriction in the event it is desired to prolong or shorten the salt wash and the rinse.

In operation, a dog 36, suitably in the form of a lug on the side of the pulley 17, is normally in engagement with the left hand side of a stop pin 37 projecting from the bracket 15, serving to hold the pulley against turning in a clockwise direction under the action of the weight 20. With the pulley so disposed, the valve 7 is set for the softening operation. When, from a test of the water or simply from observation of its characteristics, it is evident that the softener needs regenerating, the bucket 30 filled during the previous regeneration is emptied, and the arms A and B are moved counter-clockwise to the position shown, the weight 20 being correspondingly raised due to the winding of the cable 19 on the pulley 17. The stop C is retracted by hand against the action of the spring 26 to allow the arms A and B to pass the stop C and to assume the respective positions indicated, whereupon the stop is allowed to return to its normal position, as shown. The stop pin 37 is so disposed that the arm A is free to come to the position shown. The valve 7 is thus brought to the salt wash position and, during the course of the salt wash, waste water is diverted from the waste line 14 through the by-pass tube 34 into the bucket 30. This continues until the trip bucket 30 has been loaded with a predetermined amount of waste water corresponding to a predetermined duration of the salt wash, as will be evident from the foregoing description, sufficient to tilt the beam 22 and allow arm B to swing past the end of the stop C under the action of the weight 20. The valve 7 is thereby turned in a clockwise direction through 90° whereupon the end of the arm A encounters the stop C. At that time the valve 7 is in the rinse position and here again waste water is diverted from the waste line 14 to the bucket 30. The rinsing continues until the bucket 30 has been loaded sufficiently to further tilt the beam so to allow the arm A to pass the end of the stop C. The valve 7 is thus shifted again in a clockwise direction under the action of the weight 20 until the dog 36 encounters the stop pin 37, whereupon the normal softening operation of the softener is resumed.

It is believed the foregoing description conveys a clear understanding of my invention. It should be understood that while reference has been made to one specific embodiment the invention is susceptible of considerable variation in design and construction as well as in the arrangement of parts and for that reason the appended claims have been drawn to cover all legitimate modifications coming within the spirit and scope of the invention.

If desired the valve and valve operating mechanism may be so arranged that back-washing is included in the cycle of regenerating operations to precede the salt wash. The invention may be adapted to water softeners of either upflow or downflow type using any of the various well known cycles of regenerating operations.

I claim:

1. A semi-automatic regenerative base exchange water softener comprising in combination a softening tank provided with pipe connections and valve mechanism, manually operable means for setting the valve mechanism to start regeneration, mechanism operatively connected to said valve-setting means and adapted to store energy upon manually operating said means to set the valve mechanism to start regeneration, said energy storing mechanism being adapted to operate subsequently the valve mechanism, means for releasably holding said energy storing mechanism and timing means for releasing said holding means.

2. A semi-automatic regenerative base exchange water softener comprising in combination a softening tank provided with pipe connections and valve mechanism, manually operable means for setting the valve mechanism to start regeneration, mechanism operatively connected to said valve-setting means and adapted to store energy upon manually operating said means to set the valve mechanism to start regeneration, said energy storing mechanism being adapted to operate subsequently the valve mechanism, means for releasably holding said energy storing mechanism, means for releasing said holding means and means automatically controlling said releasing means in accordance with a predetermined quantity of liquid passing through the softening tank.

3. A semi-automatic regenerative base exchange water softener comprising in combination a softening tank provided with pipe connections and valve mechanism, manually operable means for setting the valve mechanism to start regeneration, mechanism operatively connected to said valve-setting means and adapted to store energy upon manually operating said means to set the valve mechanism to start regeneration, said energy storing mechanism being adapted to operate subsequently the valve mechanism, means for releasably holding said energy storing mechanism, means for periodically releasing said holding means and means automatically controlling said releasing means for several valve-setting operations in accordance with several respective predetermined quantities of liquid passing through the softening tank.

4. The combination with a water softener of valve mechanism for controlling the pipe

- connections or the equivalent for said softener in the different phases of operation thereof, said valve mechanism being arranged to be manually operated in changing from one 5 phase to another, means arranged in the manual operation to have energy stored therein sufficient to operate the valve mechanism automatically a plurality of times to change the phase thereof, and means for successively 10 rendering the last mentioned means operative to produce a plurality of successive changes in the phase of operation of the softener.
5. The combination with a softener of 15 valve mechanism for controlling the pipe connections or the equivalent for said softener for softening and regeneration, said valve mechanism normally occupying softening position and being arranged to be operated manually from softening to regeneration position, and means operable automatically after the valve mechanism has been in regeneration position for a predetermined 20 period of time to return the same to softening 25 position.
6. The combination with a softener of valve mechanism for controlling the pipe connections or the equivalent for said softener for softening and regeneration, said 30 valve mechanism normally occupying softening position and being arranged to be operated manually from softening to salt wash position, and means operated automatically when the valve mechanism has been in salt 35 wash position for a predetermined length of time to cause the operation thereof to rinse position and arranged to be operated again automatically when the valve mechanism has been in rinse position for a predetermined 40 length of time to return the same to softening position.
7. The combination with a softener of valve mechanism for controlling the pipe connections or the equivalent for said softener for softening and regeneration, said valve mechanism normally occupying softening position and being arranged to be operated manually from softening to salt wash 45 position, and means operated automatically when the valve mechanism has allowed a certain amount of fluid to pass therethrough to cause the operation thereof to rinse position and arranged to be operated again automatically when the valve mechanism has allowed 50 a certain amount of fluid to pass therethrough to return the same to softening position.
8. The combination with a softener of valve mechanism for controlling the pipe connections or the equivalent for said softener for softening and regeneration, said valve mechanism normally occupying softening position and being arranged to be operated manually from softening to regeneration position, and 55 means operated automatically when the valve mechanism has allowed a certain amount of fluid to pass therethrough to cause the operation thereof to rinse position and arranged to be operated again automatically when the valve mechanism has allowed a certain amount of fluid to pass therethrough to return the same to softening position.
9. The combination with a water softener of valve mechanism controlling the pipe connections or the equivalent for said softener in softening and regeneration, means operable both manually and automatically for operating said valve mechanism, said means being arranged to be operated manually to change from softening to regeneration, and means wherein energy is stored in the aforesaid manual operation for later operating the last mentioned means automatically when the softener has completed its regeneration to change from regeneration back to softening position. 70
10. The combination with a water softener of valve mechanism controlling the pipe connections or the equivalent for said softener in softening and regeneration, means operable both manually and automatically for operating said valve mechanism, said means being arranged to be operated manually to change from softening to salt wash, and means wherein energy is stored in the aforesaid manual operation for later operating the last mentioned means several times to change first from salt wash to rinse position and later from rinse back to softening position, the 80 said operations occurring automatically upon the completion of the said steps in the regeneration of said softener. 90
11. The combination with a water softener of valve mechanism controlling the pipe connections or the equivalent therefor in softening and regeneration, means having connection with said valve mechanism arranged to be operated manually in one direction to shift the valve from softening position to regeneration position, means wherein energy is stored in said manual operation arranged to tend to operate the same in the opposite direction back to softening position, and means for preventing the operation of said last mentioned means until the valve mechanism has been in regeneration position a predetermined length of time. 100
12. The combination with a water softener of valve mechanism controlling the pipe connections or the equivalent therefor in softening and regeneration, means having connection with said valve mechanism arranged to be operated manually in one direction to shift the valve from softening position to regeneration position, a weight raised in the manual operation arranged to tend to operate the same in the opposite direction back to softening position, and means for preventing the operation of said weight until the valve mechanism has been in regeneration position a predetermined length of time. 110
13. The combination with a water softener of valve mechanism controlling the pipe connections or the equivalent for said softener 120

- in softening and regeneration, means having connection with said valve mechanism arranged to be operated manually in one direction to shift the valve from softening position to regeneration position, means wherein energy is arranged to be stored in said manual operation tending to operate the valve mechanism in the opposite direction, a stop or catch preventing the operation of said last mentioned means, and a trip bucket arranged when loaded to a certain degree to retract said stop, said trip bucket being arranged to receive a metered stream of fluid in proportion to the flow through the softener during regeneration. 5
14. The combination as set forth in claim 13 wherein the valve mechanism during regeneration is arranged to occupy a plurality of positions, the means preventing the automatic operation of said valve mechanism comprising a plurality of parts in the nature of dogs arranged to engage the stop successively in the different positions occupied by the valve mechanism, the trip bucket being arranged to retract the stop successively for the successive operations of the valve mechanism. 10
15. The combination as set forth in claim 13 wherein the valve mechanism during regeneration is arranged to occupy a salt wash and a rinse position successively, the said means for preventing the automatic operation of said valve mechanism comprising two parts in the nature of dogs arranged successively to engage said stop in the two positions of the valve mechanism, and said trip bucket being arranged to retract the stop a certain amount at the end of the salt wash to release one of the dogs and being arranged at the end of the rinse to retract the stop still further to release the other dog. 15
16. The combination as set forth in claim 13 including spring means normally holding the stop in a certain position, the said trip bucket being arranged when loaded to counteract the action of the spring and when loaded to a certain degree to retract said stop, and means for varying the action of the spring. 20
17. The combination as set forth in claim 13 including means for varying the metered stream of fluid whereby to advance or retard the time of operation of the stop by the trip bucket. 25
18. The combination as set forth in claim 13 including a spring normally holding the stop in a certain position against the action of the trip bucket, means for varying the action of said spring whereby to affect the sensitiveness of the stop, and means for varying the metered stream of fluid delivered to the trip bucket. 30
19. The combination with a water softener of valve mechanism controlling the pipe connections or the equivalent for said softener in softening and regeneration, means having connection with said valve mechanism arranged to be operated manually in one direction to shift the valve from softening position to regeneration position, said means comprising a plurality of arms disposed in angular relation to one another, means wherein energy is arranged to be stored in the manual operation tending to operate the valve mechanism in the opposite direction, a stop arranged for engagement with the end of one of said arms to prevent the operation of said valve mechanism under the action of said last mentioned means, a spring for holding said stop in normal position, and a trip bucket arranged when loaded to oppose the action of said spring and tend to retract said stop, said trip bucket being arranged to receive a metered stream of fluid in proportion to the flow through the softener during regeneration, said trip bucket when loaded to a certain degree serving to retract said stop a certain amount whereby to permit the end of one of said arms to pass the same, and said trip bucket when loaded still more serving to retract the stop farther whereby to allow the end of the next arm to pass the same. 35
20. The combination with a softener of valve mechanism for controlling the pipe connections or the equivalent for said softener for softening and regeneration, said valve mechanism normally occupying softening position and being arranged to be operated manually from softening to regeneration position and a mechanism arranged to be wound up in the manual operation of said valve mechanism from softening to regeneration position and tending thereafter to operate the valve mechanism back to softening position, said mechanism being arranged to unwind during the regeneration to bring the valve mechanism back to softening position. 40
21. The combination with a softener of valve mechanism for controlling the pipe connections or the equivalent for said softener for softening and regeneration, said valve mechanism normally occupying softening position and being arranged to be operated manually from softening to regeneration position, and a mechanism arranged to be operated in a moment by hand in the manual operation of the valve mechanism from softening to regeneration position and tending thereafter to operate the valve mechanism back to softening position, said mechanism being arranged to take appreciable time to get back to its initial position and being thereby arranged to predetermine the duration of the regeneration operation. 45
22. The combination with a softener of valve mechanism for controlling the pipe connections or the equivalent for said softener for softening and regeneration, said valve mechanism normally occupying softening position and being arranged to be operated manually from softening to regeneration. 50

- tion position, and a device arranged to be loaded in the hand operation of said valve mechanism from softening to regeneration position and tending thereafter to operate the valve mechanism back to softening position, said device having means for permitting the same to unload itself only in a predetermined time whereby to automatically operate the valve mechanism back to softening position only after a predetermined period of regeneration. 70
23. The combination with a softener of valve mechanism for controlling the pipe connections or the equivalent for said softener for softening and regeneration, said valve mechanism normally occupying softening position and being arranged to be operated manually from softening to regeneration position, a part arranged in the manual operation of the valve mechanism from softening to regeneration position to be raised, said part thereafter tending to gravitate to its initial position and thereby operate the valve mechanism back to softening position, and means arranged to permit gravitation of said part only after a predetermined time has elapsed from the commencement of the regeneration whereby to predetermined the period of regeneration. 80
24. The combination with a water softener of valve mechanism controlling the pipe connections or the equivalent therefor in softening and regeneration, means having connection with said valve mechanism arranged to be operated manually in one direction to shift the valve from softening position to regeneration position, means wherein energy is stored in said manual operation arranged to tend to operate the same in the opposite direction back to softening position, and means for preventing the operation of said last mentioned means until the valve mechanism has allowed a certain amount of fluid to pass through the softener during regeneration. 90
25. The combination with a water softener of valve mechanism controlling the pipe connections or the equivalent therefor in softening and regeneration, means having connection with said valve mechanism arranged to be operated manually in one direction to shift the valve from softening position to regeneration position, a weight raised in the manual operation arranged to tend to operate the same in the opposite direction back to softening position, and means for preventing the operation of said weight until the valve mechanism has allowed a certain amount of fluid to pass through the softener during regeneration. 100
26. The combination with a water softener of valve mechanism controlling the pipe connections or the equivalent for said softener in softening and regeneration, a fixed stop, a part in the nature of a dog associated with the valve mechanism normally engaging said stop when the valve mechanism is in softening position, means having connection with said valve mechanism arranged to be operated manually in one direction to shift the valve from softening position to regeneration position, means wherein energy is arranged to be stored in said manual operation tending to operate the valve mechanism in the opposite direction, one or more other parts in the nature of dogs associated with the valve mechanism arranged to hold the valve mechanism in one or more other positions for regeneration, a movable stop arranged to be engaged by the last mentioned parts in the one or more regeneration positions, and means for retracting said stop automatically when the valve has been in a regeneration position for a predetermined period of time. 110
27. The combination with a water softener, of valve mechanism controlling the pipe connections or the equivalent for said softener in softening and regeneration, means having connection with said valve mechanism arranged to be operated manually in one direction to shift the valve from softening position through a plurality of phases to start regeneration, means wherein energy is arranged to be stored in said manual operation tending to operate the valve mechanism in the opposite direction, one or more parts in the nature of dogs associated with the valve mechanism arranged to hold the valve mechanism in one or more positions of regeneration, a movable stop arranged to be engaged by the last mentioned parts in said regeneration positions, and means for retracting the stop automatically after the valve has been in a certain position for a predetermined period of time. 120
28. The combination set forth in claim 27, wherein the dogs are of graduated lengths and wherein the movable stop in its first position is engaged by the shortest dog to hold the valve mechanism in a certain position, and after movement is arranged to be engaged by the next longer dog, and so forth. 130
29. The combination set forth in claim 27, wherein the dogs are of graduated lengths and wherein the movable stop in its first position is engaged by the shortest dog to hold the valve mechanism in a certain position, and after movement is arranged to be engaged by the next longer dog, and so forth, and wherein the means for retracting said stop comprises a trip bucket arranged to receive a stream of water during regeneration and arranged when loaded to a certain extent to move the stop a certain distance and when loaded to a still further extent to move the stop farther, and so forth. 125
30. In combination with a base-exchange water softener having a circulation system by which water is passed through the softener to service in the normal softening operation 130

- and by which liquids from different sources are passed through the softener and discharged otherwise than to service for operations other than normal, valve-means controlling said system, the valve-means being normally in position for the softening operation, and valve operating and controlling mechanism adapted to be placed in operative condition by setting the valve-means in position for the first operation other than normal, said mechanism when so rendered operative causing successive operations of the valve-means as required to complete the cycle of operations other than normal and resumption of normal operation and maintaining the valve-means in each position other than normal for a predetermined period before moving the valve-means to the next position.

In witness of the foregoing I affix my signature.
